UNITED STATES PATENT OFFICE.

HENRY B. HAIGH, OF NEW YORK, N. Y.

ELASTIC HEEL FOR SHOES.

SPECIFICATION forming part of Letters Patent No. 636,796, dated November 14, 1899.

Application filed August 8, 1899. Serial No. 726,551. (No model.)

To all whom it may concern:

Be it known that I, HENRY B. HAIGH, a citizen of the United States, residing at New York, (Brooklyn,) county of Kings, and State of 5 New York, have invented certain new and useful Improvements in Elastic Heels for Shoes, of which the following is a full, clear, and exact description, reference being had to the accompanying drawings, forming part of this 10 specification.

My invention relates to devices intended to give elasticity to the heel of a shoe in walking, to prevent slipping, to aid in the comfort of the shoe in use, and to render more durable 15 and less liable to wear the ordinary leather heel.

It has long been customary to provide rubber plates of various kinds for shoe-heels; but in all such shoes that I am acquainted with 20 the rubber is so secured that in a very short time the plate is worn down to the leather heel and a new plate must be provided or all benefits from the elastic heel are parted with.

It is the purpose of my invention to provide 25 an elastic tread for the heel which shall wear down no faster than the leather heel and which by its method of construction and fastening shall prevent scuffing or slipping, and thus largely decrease the ordinary wear on 30 the leather heel. This I accomplish by a certain novel construction and arrangement to be hereinafter particularly pointed out and claimed.

In the drawings, Figure 1 is a perspective 35 view of the sole of an ordinary shoe with my improvement in place. Fig. 2 is a perspective view of the heel with the top lift slightly removed. Fig. 3 is a cross-section of the top lift.

40 A is an ordinary shoe provided with the usual heel B.

C is the top lift, in which is cut a groove a, preferably around the lift from one inner edge to the other. This groove is beveled or flared 45 inwardly, and within this groove is inserted a rectangular strip of rubber b or other like material slightly thicker than the lift, so as to allow the rubber to extend slightly above the tread-surface of the lift, as shown at f, Fig. 50 3. The top lift is then spanked on the other steel-pegged lifts in the usual way, and the shoe is ready for use. To hold the rubber

strip in place, I prefer to leave a slight tongue c to the rubber, and a single nail may then be driven through the lift and this tongue to secure the strip against displacement; but many methods of holding or securing the strip will readily suggest themselves, and I do not wish to limit myself to any particular method. The peculiarity of my elastic heel over any others 55 in use lies in the fact that the strip only extends slightly above the ordinary heel-surface and that spaces d d are left within the groove, owing to its dovetailed construction, within which the rubber can expand when external 60 pressure is brought to bear thereon in use. When the heel is brought down in walking, the rubber at once grips the surface, prevents any sliding, slipping, or scuffing, and then under the pressure of the weight of the user 65 the rubber compresses vertically flush with the surface and expands laterally into the side spaces d d, preventing any undue wear on the rubber and allowing the contact wear to come on the leather; but by reason of the fact that 70 the rubber first grips the surface the ordinary wear on the leather is very much reduced and what wear there is always retains the rubber surface in the same relative position to the leather surface, slightly projecting therefrom. 75 This is due to the peculiar relation which exists between the wearing qualities of leather and the wearing qualities of the rubber strip under the conditions of use above described. This relation is such that it produces the 80 result that the rubber always projects beyond the surface of the heel and is not worn down level with that surface, because the rubber does not take all the wear and the leather of the heel wears away as fast as does the rubber of the projecting strip. Hence the rubber strip retains its prominence until it is worn out. It is obvious, however, that other materials having substantially the same wearing 85 properties as leather would be the equivalent 90 of leather in this combination.

The particular shape of the groove for retaining the rubber strip and the width and thickness of the strip are of course not material, so long as there is maintained such relation between the projecting rubber and the side spaces of the groove that the amount of contraction of the rubber under compression 95 may be taken up in the space for expansion.

It is not essential that a single strip of rubber should be used or that the grooves should be dovetailed, as shown, provided that space is left within the groove for the expansion of the rubber and that the rubber only extends a slight distance above the tread-surface of the heel. A plurality of strips may be used and the groove recessed to leave space for expansion without dovetailing.

10 Having thus described my invention, what I claim, and desire to secure by Letters Patent, is—

15 1. A heel for shoes made of leather, provided with a recess in the lower-surface of the heel, and a rubber piece fitting in said recess, but not completely filling the same, with the upper surface extending only slightly above the outer surface of the heel, with means for holding said rubber piece in place, substantially as described.

20 2. A heel for shoes, provided with a recess in the lower surface of the heel, and a rubber piece fitting in said recess, but not completely filling the same, with the upper surface 25 face of the rubber extending only slightly

above the outer surface of the heel, and a tongue on the rubber piece extending between the top lift and heel for holding the said rubber piece in place, substantially as described.

3. In a heel for shoes, a top lift therefor, 30 made of leather, provided with a slot wider within than at the surface, and a rubber strip fitting in said slot but not completely filling the same, and means for retaining said strip within the slot, substantially as described. 35

4. In a heel for shoes made of leather, the combination, with the heel, of the top lift therefor provided with a slot having walls flaring inwardly, and a rubber strip fitting in said slot but not completely filling the same, 40 with the upper surface of the rubber extending only slightly above the outer surface of the top lift, and a tongue on the strip extending between the top lift and the heel for retaining the strip in place, substantially as described. 45
